UNITED STATES PATENT OFFICE.

ANTHONY KRIBS, OF BROOKLYN, NEW YORK.

DESIGN FOR THE ORNAMENTATION OF GLOBES AND SIMILAR ARTICLES.

SPECIFICATION forming part of **Design No. 17,149, dated March 1, 1887.**

Application filed June 28, 1886. Serial No. 206,545. Term of patent 3½ years.

To all whom it may concern:

Be it known that I, ANTHONY KRIBS, a citizen of the United States, residing in Brooklyn, in the county of Kings and State of New York, have invented and produced a new and original Design for Globes, Vases, and other Similar Articles, of which the following is a specification, reference being had to the accompanying photograph and drawings, forming a part thereof.

Figure 1 is a photograph of a globe representing my design. Figs. 2 and 3 are sectional views, these views being deemed necessary to fully illustrate my said design.

5 The leading feature of my said design consists of a globe having thereon a raised band or border having a beveled edge, forming the hexagon figures A and B, the angles of which may be equal or not, as represented in said figures, with a raised round or oval

pointed bulb or projection, C, in the center of each hexagon figure. Heretofore glass globes and other glasswares have been ornamented with such raised or relieved bulbs or 25 projections C, but without the raised band or border forming the hexagon figure aforesaid.

I claim—

The design for the ornamentation of globes, vases, and other similar articles, the same consisting of a continuous and connected raised 30 band or border, A, having a beveled edge, forming a series or number of hexagon figures, with the raised and pointed bulb or projection C in the center of each hexagon figure, as shown and described.

ANTHONY KRIBS.
